UNITED STATES PATENT OFFICE.

NICHOLAS B. MCGHEE AND ROSAL K. ACUFF, OF TEMPE, ARIZONA.

DUPLEX DIRT-WAGON.

1,075,926.

Specification of Letters Patent. Patented Oct. 14, 1913.

Application filed July 19, 1912. Serial No. 710,298.

To whom it may concern:

Be it known that we, NICHOLAS B. MCGHEE and ROSAL K. ACUFF, both citizens of the United States, and residents of 5 Tempe, in the county of Maricopa and State of Arizona, have invented a new and Improved Duplex Dirt-Wagon, of which the following is a full, clear, and exact description.

10 The object of the present invention is to provide a receptacle mounted on wheels for the purpose of temporarily receiving the earth which is removed from a grave preparatory to the interment of the dead so that 15 such earth may be temporarily removed from the vicinity of the open grave and concealed during the services attendant at the burial and thus permit of a gathering of the friends and relatives about the grave during 20 the services without the inconvenience attendant upon the piling of the earth upon the ground adjacent the grave and also to insure a sightly appearance of the surroundings during the funeral services.

25 The invention is hereinafter described and the novel features specifically indicated in the claim.

Reference is to be had to the accompanying drawings, constituting a part of this 30 specification, in which similar characters of reference denote corresponding parts in all the views and in which—

Figure 1 shows a top plan view of the dirt wagon and the coöperative conveyer in position to receive the earth as it is removed from the open grave; Fig. 2 shows an end elevation of the dirt wagon and the conveyer connected thereto, in position to receive the earth from the grave; and Fig. 3 40 shows the dirt wagon and conveyer discharging its contents into the open grave.

The dirt receptacle 1 is preferably cylindrical in form and of a size to conveniently hold the desired load of dirt. It is preferably provided with a plurality of chambers 2 formed by the longitudinally extending partitions 3 which extend from end to end upon the interior of the receptacle 1 and are disposed at an angle to each other. The 45 inclosing cylindrical wall 4 is provided with longitudinal openings 5 giving access to the chambers 2, and these openings 5 are closed by removable covers 6 which are secured in position by means of pivoted hasps 7 connected to the covers 6 and which are arranged to overlap upon the upper surface of

the adjacent covers 6 and to engage headed turn-buttons 8 which are screwed into the covers 6 along the outer edges. The cylindrical receptacle 1 is mounted upon a shaft 10 supported at its opposite ends in bearings 11 carried by vertical arches 12. The yokes 12 are mounted upon the opposite ends of a bar 13 which is provided with a fifth wheel or bearing 14 which rests upon a similar bearing 15 carried by a frame 16 and which is pivotally connected to the bar 13 in any usual or convenient manner. The dirt receptacle 1 is made of less length than the distance between the truck wheels 19 in order to provide space for manipulation of the hinged doors of the same and the proper application and arrangement of the dirt conveyer, as hereinafter described. The frames 16 at opposite ends are provided 75 with bearings 17 in which are mounted the axles or trunnions 18 carrying the wheels 19. The frames 16 are provided with sockets 20 to which may be fitted a pole 21 secured detachably by means of the bolt 22. It is to be observed that the pole 21 is thus 80 adapted for connection with either end of the truck so as to draw the dirt wagon in either direction. The arches 12 are connected by longitudinally extending tie rods 23 whereby rigidity and strength are secured.

Coöperating with the receptacle 1 is provided a suitable conveyer consisting of the side frames 24 supporting at either end 90 rollers 25 over which is tightly drawn a belt 26 or any suitable flexible carrier having the necessary strength, and to the outer surface of which are fixed in any suitable manner, transversely extending slats 27. The lower 95 roller 25 is provided with a crank 28, or there may be two cranks one located at opposite ends as shown in Fig. 1 of the drawing whereby the roller may be turned in its bearings to cause the conveyer belt 26, 27 to 100 move in a direction to carry the dirt upward from the open grave and deliver it to the receptacle 1, or to receive dirt from such receptacle and deliver it to the open grave. Suitable pawl and ratchet mechanism such 105 as the pawls 29 and the ratchets 30 may be provided to prevent downward movement of the elevator when used for loading as shown in Fig. 2. The elevator is provided with means for supporting it adjacent to 110 the receptacle 1 either in the elevated position shown in Fig. 2 wherein the conveyer is

used for delivering dirt to the receptacle or in the lower position as shown in Fig. 3 where the elevator is used for receiving dirt from the receptacle and delivering it to the open grave. As shown the support consists of pairs of legs 31 and 32 pivoted respectively near the ends of the elevator frame 24, the legs 32 being quite short so as to support the outer end of the elevator a little above the edge of the grave, as shown in Figs. 2 and 3. The legs 31 are connected by means of pivoted links 33 to the frame 24, and as shown in Fig. 2, there is a detachable connection between the links 33 and the legs 31 whereby they may be dropped to the position shown in Fig. 3 when the conveyer is lowered for receiving dirt from the receptacle to be delivered to the open grave.

In order to turn the receptacle 1, the shaft 10 is provided at either end with a sprocket wheel 34 which is engaged by a sprocket chain 35 which is driven by a similar sprocket wheel 36 mounted upon a stud 37, on the yokes 12, and which may be turned by a crank 38 whereby through the chains 37 to turn the receptacle.

In operation, the apparatus is positioned as shown in Fig. 2 adjacent the edge of the grave to be opened, and the dirt which is removed from the grave is placed upon the elevator, and as it is placed thereon, cranks 28 may be operated to cause the elevator to travel upward and discharge the dirt at its upper end into one of the chambers of the receptacle. When one of the chambers has been filled, its door 6 will be turned down and securely fastened and the receptacle revolved to bring another chamber into filling position. After the dirt has been removed from the grave and the receptacle filled, the

elevator is disconnected therefrom and removed to a suitable storage place away from the vicinity of the grave, leaving a free and clear space around the grave for the accommodation of the friends of the deceased during the funeral services. After the funeral services are over, the wagon is drawn into the position shown in Fig. 3 in which the elevator is in its lowermost position. Thus the cylindrical receptacle may be revolved to deposit dirt on the elevator which will convey it into the grave.

Having thus described our invention, we claim as new and desire to secure by Letters Patent:

A dirt wagon comprising a wheel truck having vertical parallel arches fixed on its axles, a cylindrical dirt receptacle arranged longitudinally of said truck so that it extends between the front and rear axles, the length of the receptacle being less than the distance between the front and rear wheels of the truck, a central shaft for said receptacle which is journaled in the aforesaid arches, the receptacle having a plurality of dirt-receiving chambers extending the whole length of the same and provided with side openings of the same length and having covers for closing them, and sprocket mechanism arranged between the front end of the cylinder and the adjacent arch, as described.

In testimony whereof we have signed our names to this specification in the presence of two subscribing witnesses.

NICHOLAS B. McGHEE.
ROSAL K. ACUFF.
